(57) **CLAIM**

The ornamental design for a seat portion for a trike, bike or the like, as shown and described.

DESCRIPTION

FIG. 1 is a perspective view of an embodiment of my new, original and ornamental design;

FIG. 2 is a front view thereof;

FIG. 3 is a rear view thereof;

FIG. 4 is a right side view thereof, the left side view being a mirror image thereof;

FIG. 5 is a top view thereof; and,

FIG. 6 is a bottom view thereof.

The phantom lines shown are directed to environment and form no part of the claimed design.
